UNITED STATES PATENT OFFICE.

JOSEF GRANZ, OF PLAUEN, GERMANY, ASSIGNOR TO VOGTLÄNDISCHE MASCHINEN-FABRIK, OF PLAUEN, GERMANY.

EMBROIDERING-MACHINE SHUTTLE.

1,266,117.

Specification of Letters Patent. Patented May 14, 1918.

Application filed September 16, 1914. Serial No. 862,054.

To all whom it may concern:

Be it known that I, JOSEF GRANZ, a subject of the German Emperor, residing at Plauen, in Vogtland, in the Kingdom of 5 Saxony, Germany, have invented certain new and useful Improvements in Embroidering-Machine Shuttles, of which the following is a specification.

The present invention relates to embroidery machine shuttles of the kind described and shown in the United States Patent No. 1,082,456, issued Dec. 23, 1913, and has for its object to improve its construction, so that while in operation it will remove from the 15 shuttle bed the refuse or dirt formed by fibers, dust and oil accumulating thereon and thus always maintain the bearing surfaces clean and smooth.

I accomplish my object by providing the 20 bearing surface of the shuttle with a recess or opening having outer sharp edges which are adapted during the movement of the shuttle to shove the refuse off the raceway or bed or gather it up into said opening.

Particularly with a shuttle having its 25 bearing surface formed at a right angle to the covered filling opening which is directed toward the stitch plate, the evil resulting from accumulation of dirt on the bed and 30 bottom of the shuttle becomes very noticeable.

With a shuttle in which the filling opening is arranged at the bottom, the outer edges surrounding the said opening and forming 35 the bearing edges remove the dirt, and prevent its accumulation. But a shuttle that bears on the bed with a solid surface instead of cleaning the bed, spreads the dirt over it. This is very objectionable and the removal 40 of the dirt when using the shuttles of the type above referred to presents a comparatively difficult problem, which is solved by the present invention.

In the accompanying drawing, which 45 forms part of my invention and in which similar reference characters denote corresponding parts, Figure 1 is a bottom plan view of a shuttle constructed in accordance with my invention; Fig. 2 is a cross section thereof; Fig. 3 is a similar view as Fig. 1 of a modified structure; Fig. 4 is a side elevation thereof, showing the depth of the groove or recess in the bearing or bottom surface; Fig. 5 is a bottom plan view of another modification; Figs. 6 and 7 are bottom plan

views of further modifications; Fig. 8 is a vertical longitudinal section of the modified shuttle shown in Fig. 6 and Fig. 9 is a similar section of a further modification.

Referring specifically to the drawing and 60 particularly to Figs. 1 and 2 *a* denotes a shuttle which is constructed and arranged substantially as that of the above-named patent. *a'* denotes the bearing or bottom surface formed by one of the solid walls of 65 the shuttles, while the filling opening *a*² closed by the cover *a*³ is arranged at the side or at a right angle to said surface to be directed when in use toward the stitch plate *b*. The sole or bottom *a'* is provided with a 70 groove or recess *a*⁴ arranged midway between the ends of the shuttle and extending cross-wise throughout the entire width of the bottom *a'*. The edges *a*⁵ are adapted during 75 the movement of the shuttle to gather up and throw off the dirt from the shuttle bed. While the outer edges *a*⁶ surrounding the sole or bottom of the shuttle must not be sharp, but more or less rounded, lest the needle thread be cut when the shuttle passes 80 through the loop, the edges *a*⁵ being located on the inside do not affect the thread and are therefore made sharp in order to more effectively remove the dirt.

In the modification according to Figs. 3 85 and 4 the recess *d* narrows down from the sides or edges *a*⁵ toward the longitudinal central line, forming dart-shaped sharp edges *c*. These edges will not only remove the dirt from the shuttle bed but at the same 90 time also shove it outwardly.

In the modification according to Fig. 5 the recess *e* has sharp curved edges *e'* and dart-shaped edges *e*².

In the modifications according to Figs. 95 6 and 7 the bottom or sole *a'* of the shuttle instead of being solid is provided with a longitudinal opening *f* which like in the former type of shuttles forms a sharp angular edge *f'* that constitutes the bearing surface of the shuttle. In Fig. 6 the forward end *f*² of the edge *f'* is more or less curved, while in Fig. 7 the end *f*³ is pointed. The edge *f'* serves also to gather up the dirt into the opening *f*.

On its inside the opening *f* may be covered by a thin metal sheet or plate *g* (Figs. 6 and 8) to prevent the bobbins from slipping out through the opening *f* and coming in contact with the shuttle bed.

In the modification according to Fig. 9 the opening *h* in the bottom *a'* of the shuttle is provided with an inwardly projecting flange *i* on which the bobbin *b* is adapted to rest. This flange serves primarily the object to hold the bobbin *b* at a sufficient distance from the shuttle bed, without using the plate *g* (Figs. 6 and 8) and secondly to provide a deeper space to be capable of gathering up more dirt, and thereby avoiding the repeated cleaning of the shuttle.

What I claim and desire to secure by Letters Patent is:

An embroidering machine shuttle the bearing surface of which has an opening serv-

ing as dirt accumulating chamber and having sharp edges adapted to scrape up the dirt accumulating on the shuttle race and flanges inside the shuttle projecting around said opening and serving to support the bobbin at a greater distance away from the bearing surface than the thickness of the shuttle wall and to deepen the said chamber.

In testimony whereof I affix my signature in presence of two witnesses.

JOSEF GRANZ.
